UNITED STATES PATENT OFFICE

2,120,649

MACHINE FOR MAKING CAPPED NUT
BLANKS

Heyman Rosenberg, New York, N. Y.

Original application May 21, 1935, Serial No. 22,593, now Patent No. 2,090,641, dated August 24, 1937. Divided and this application June 18, 1937, Serial No. 148,895

9 Claims. (Cl. 10—76)

This application is a division of my pending application Serial No. 22,593, filed May 21, 1935, for Art of producing capped nut blanks. In that application disclosure is made of methods and apparatus for die-forming capped nut blanks from either slugs or sheets of metal. Briefly the method, which is both disclosed and claimed in said application, involves die-forming a slug or disc of metal into a thimble-like shell or blank, and then die-forming the thimble-like blank to convert it into a blank having the proper external and internal configuration of a finished, but unthreaded, capped nut.

The said application also discloses but does not claim three machines used in practicing the claimed method; namely, a machine for forming the thimble-like blanks from slugs of metal, a machine for forming the thimble-like blanks from a sheet of metal, and a machine for converting the thimble-like blanks into unthreaded capped nut blanks. The present application is concerned with the first of these machines, the one which forms thimble-like blanks from slugs of metal.

It is an object of the present invention to provide a machine capable of die-forming thimble-like blanks from solid slugs of metal.

It is a further object of the invention to provide a machine for die-forming thimble-like blanks from solid slugs of metal without substantial waste of material.

It is a still further object of the invention to provide a machine constructed and organized to form thimble-like blanks rapidly and effectively and in an automatic manner from wire stock fed into the machine, with substantially no other attention or supervision than the occasional placing of a fresh reel of wire stock in position to be fed to the operating instrumentalities of the machine.

To these ends, a very advantageous and practical form of machine embodying the invention desirably consists of a double stroke standard header, embodying instrumentalities enabling the machine rapidly and automatically to convert slugs of metal into thimble-like blanks by a succession of die-forming operations performed upon each blank. The machine desirably includes means for intermittently feeding wire from a wire reel through steps of measured length, and mechanism for severing a slug of metal from the leading end of the wire after each wire feeding step and for transferring the severed slug to alignment with a stationary, female, forming die.

A double stroke reciprocating plunger, operating

in timed relation to the slug-severing and transferring mechanism, carries two forming dies for cooperating with the female die at alternate forward strokes of the plunger. The first or preliminary forming die thrusts the slug into the female die and shapes it exteriorly to substantially the contour of the female die to form one end of the slug to substantially the dome shaped contour of the finished blank. The preliminary die also forms a central recess or depression in the end face of the slug which it engages. The second forming die, which is the finishing die, carries a finger for die-forming the interior cavity of the blank. The blank is carried away from the female die upon the finishing die and is then carried forward, out of alignment with the female die, at the non-forming stroke of the finishing die. A stripper is provided for engaging behind the thus advanced blank and stripping blank from the finishing die as the die recedes.

Other objects and advantages will hereinafter appear.

In the drawings forming part of this specification and illustrating an advantageous and practical embodiment of the invention

Figure 1 is a view partly in side elevation and partly in vertical section of a double stroke header embodying features of the present invention;

Figure 2 is a view in elevation, partly broken away, of a piece of work material, such as a fragment or slug severed from wire stock, which is converted through the instrumentalities of the present invention into a thimble-like shell;

Figure 3 is a longitudinal sectional view through such a slug as that illustrated in Figure 2 at the conclusion of the first or preliminary forming operation;

Figure 4 is a longitudinal sectional view of the blank of Figure 3 after the second or finishing forming operation;

Figure 5 is a view partly in plan and partly in horizontal section of the header of Figure 1, the parts being shown on a scale somewhat larger than the scale of Figure 1;

Figure 6 is a fragmentary, detailed view showing the plunger dies of Figures 1 and 5 in elevation and other parts in section, the parts being shown in the positions which they occupy at the conclusion of the preliminary forming stroke;

Figure 7 is a view similar to Figure 6, but showing the parts in the positions which they occupy at the conclusion of the finishing forming stroke;

Figure 8 is a view in front elevation of the die block and stripper means, parts being broken

away and shown in section for disclosing otherwise concealed parts;

Figure 9 is a fragmentary, side elevation of the matrix die block showing the stripper in end view; and

Figure 10 is a horizontal section taken on the plane indicated by the line 10—10 of Figure 8, and looking in the direction of the arrows.

As previously indicated, the illustrative machine is a form of standard double stroke header, having instrumentalities embodied in it for enabling it to convert a slug like that of Figure 2 into a thimble-like blank as shown in Figure 4, by die-forming operations.

It is, of course, well understood in the industry that a header is a machine for forging enlargements on the ends of wire or rod blanks in the course of manufacturing nails, screws, bolts, and like fasteners. One of the earlier and simplest forms of such headers is seen more or less diagrammatically in the patent to T. Ferry, No. 1,069,659, dated August 5, 1913. The header shown in the said Ferry patent is of the double-stroke type, that is to say, a forming or matrix die is located to receive material to be treated by two plunger dies, one of which is caused to approach and act upon the material at one stroke of the machine, and then to shift out of line while the other shifts into line and acts on the material during the next stroke. The headers have become somewhat more complicated and more efficient than the illustration in the patent just mentioned, but the principle generally remains the same in the two-stroke headers. An illustration of a modern and efficient header is found in the product now being marketed by the Waterbury Farrel Foundry and Machine Company, of Waterbury, Connecticut, and the present invention is well adapted to be incorporated and embodied in such a header, and especially in a header of the type popularly referred to as solid-die, double-stroke, high speed crank header. Parts of this header are disclosed in the patent to C. O. Petitjean, No. 1,478,356, dated December 18, 1923. Parts commonly known and popularly used on such headers are in part omitted and in part shown in the accompanying drawings, so much only being illustrated as is adapted for facilitating disclosure of the present invention. Detailed description of parts that are thus commonly known and are not directly modified by the present invention is omitted as not needed.

Referring to the drawings by numerals, the apparatus seen in Figures 1 to 10 inclusive consists essentially of a header having the usual pitman 1 journaled on an actuating crank and pivoted to impart the requisite thrusts to the die block 2. A plunger slide 3 is carried by the die-block 2 in position to slide vertically thereon, or across the rectilinear horizontal path of the die block 2 while being carried thereby and receiving its thrust therefrom. A punch holder 4 is mounted on the plunger slide 3 and carries the punches or plunger dies 5 and 6 which are spaced vertically apart. An appropriate apparatus, such as a crank 7 and its connected parts, imparts timed, vertical shifting movement to the plunger slide 3 to cause the punch or plunger die 5 first to operate and then to move up out of line, and then the punch or plunger die 6 to operate.

Of course, the parts just described are appropriately mounted in a suitable bed or framework 7 having an internal space accommodating the

plunger dies 5 and 6 spaced from the cooperating, opposed matrix die 8. At one side of the die 8 is a cut-off die 9 and a laterally reciprocating cutter bar 10 (corresponding to cutter 14 of said Petitjean patent) with which cooperates the spring-stressed clamping finger 11 carried by the fiddle bow (not shown but seen at 17 in said Petitjean patent, finger 11 corresponding to finger 21 of said patent) for clamping the material severed by the bar 10 against the bar while the bar is moving into line with the die 8. A reciprocating cutter slide 12 (corresponding to slide 13 of the Petitjean patent) carries the shearing bar 10. Slide 12 is reciprocated in timed relation to the action of the die block 2, and the plunger dies 5 and 6. Thus, shearing bar 10 successively severs a slug or blank from a supply of wire or rod fed through die 9, moves the slug over to alignment with matrix die 8, with the cooperation of finger 11, releases the blank or slug, and returns to cut off the next blank or slug in timed relation to the movements of the other cooperating parts.

In nail making headers, the die corresponding to die 8 is the heading die, and appropriately recessed punches are carried by the punch holder 4 to cooperate with the blank in the heading die. According to the present invention, however, the punches or plunger dies 5 and 6 are not the ordinary heading cone punches but are especially constructed and incorporate features of the present invention. It will be noted that the die 8 is provided centrally with a recess 13 into which the material of the blank is to be forced in giving the blank its initial and second shapes. To this end, the plunger die 5 is provided with a preferably cylindrical, reduced extension or projection 14 terminating in a part-globular or bulbous extension 15, centrally, axially located. The free end surface of the projection 14 with the exception of the bulbous part 15 is flat, and the projection 14 is of a diameter to snugly fit within and slide into the die recess 13 for effectively forging the slug or piece of work material comprising the blank 16 of Figure 2 against the inner end and sides of the recess 13 to substantially the condition seen at 16' in Figure 3, with the depression 19 in its outer end. Irregularity in the original shape of the blank 16 is not objectionable so long as the material is of such contour and quantity that it can be successfully forced into the die recess 13 and there cold forged into the form of a thimble-like shell 20, seen detached in Figure 4.

Whether the work material be a slug, as seen at 16 in Figure 2 cut from a supply of wire or rod, or a slug otherwise produced, the slug is held, as by cutter bar 10 and finger 11, in line with the die recess 13 as the die block 2 is concluding the first forward stroke, so that projection 14 with its rounded extension 15 engages the slug and forces it into recess 13 and compresses it sufficiently for cold forging it and causing it to conform substantially to the contour of the die recess 13 and to thus assume the shape 16' of Figure 3. Then the die block 2 recedes and leaves the work material 16' in the die recess 13.

Before the next advancing stroke of die block 2, the punch slide is shifted upward by the action of the crank 7 and cooperating parts until the plunger die 6 is brought into line with the die recess 13. Plunger 6 is provided with an axially outstanding shaping finger 18 which, in the forward stroke of die block 2, enters the recess 13 and enters the centering depressing 19 of blank 75

16', and the further advancing movement of the finger 18 causes the material of blank 16' to be flowed both laterally into more compact condition, and longitudinally into greater length, moving outward along the die finger 18 to the position substantially as indicated in Figure 7, so that the work material in the die recess 13 is thus caused to assume the contour seen in Figure 4, or substantially that contour. It should be understood that the showing of the work material in Figures 2, 3, 4, 6, and 7, is more or less idealized as expressing the characteristic contours given to the work material as the process progresses; but it should be further understood that slight departures from such contours, such, for instance, as some little irregularity about the outer margin or free edge of the thimble 20 as seen in Figure 4, or some slight flattening of the parti-globular or rounded inner end thereof as seen in Figure 3 is not of any materiality, such irregularity being effectively corrected in the next succeeding steps of the process.

It is important that the amount of material in the blank or slug, such as seen in Figure 2, be substantially that required for the completed article, and it will, of course, be understood that when the slug or fragment of wire, as seen in Figure 2, is employed, the operation begins with the cutting off of the slug from the supply wire or rod seen at 21. This supply wire or rod 21 is passed between the feeding rolls 22 which are part of the standard equipment of the header machine, and the wire or rod is extended through the cut-off die 9 where the protruding end portion is severed by the cross stroke of the shearing bar 10. The spring finger 11 resiliently stresses the portion being cut off against the shearing bar 10 and continues to frictionally hold the slug after it is severed while the bar 10 is functioning as a carriage to move the slug over into line with the recess 13. Properly timed with this movement the plunger die 5 approaches and begins to press the slug 16 into the recess 13, and thereupon bar 10 moves back and spring finger 11 releases the slug and rides over plunger 5 back to again engage the protruding end portion of wire 21. Wire 21 is of course fed through the die 9 into position for being cut off for supplying the next slug in timed relation to the other movements of the machine. It should be understood that the feeding rolls 22 and cut-off die 9 (as well as the shearing bar 10 and spring finger 11) are standard equipment of well known types of headers for use in the making of nails, screws, bolts, and the like, and that the feeder rolls 22 are provided with appropriate adjustment and control devices for feeding forward the desired and requisite quantity only of the wire or rod 21 to be severed by the shearing bar 10. Wire or rod 21 may be steel, copper or other material according to the product desired.

A knock-out pin 23 is part of the standard equipment of a header, and, in the present construction, extends through the die 8 and axially into the recess 13, said pin extending through a portion of the framing 7' in position to be engaged by the free end of an actuating lever 24, pivoted at 33 to swing in timed relation to the strokes of the die block 2 to cause the pin 23 to have a knock-out stroke at every alternate stroke of die block 2 as the die finger 18 is receding.

However, the said knock-out pin 23 and its operation are largely only precautionary, since the thimble 20, when completed about the finger 18, usually clings to the finger with a frictional

engagement requiring the thimble to be stripped from the finger to prepare the finger for the next operation. To that end, the stripping mechanism seen in Figures 6 to 10 inclusive is provided. As best seen in Figures 7 and 8, the die engaging block 25 for die 8 is provided with a recess 26 to accommodate the projection 14 on the second stroke of the die block 2, the recess 26 being spaced above and in vertical alignment with the recess 13 and centered to correspond with the respective centering of the projection 14 and the finger 18. Ordinarily, in headers of the type shown, the space below the recess 13 corresponding to the location of the finger 18 when projection 14 is in a recess corresponding to recess 13 is merely an open space, but, according to the present invention, provision is made for engaging the thimble 20 on the finger 18 and stripping the same therefrom while beneath the die 8. Accordingly, a detent is provided for the thimble 20 that allows the free movement of the finger. To this end, an appropriate framework 27 is arranged beneath the die 8 and provided with slide plates 28, 29, each having a semi-circular notch at its inner end facing the corresponding notch of the other slide plate so as to provide a passageway or opening 29 through which the finger 18 may freely move. That is to say, the passageway 29 is of a sufficient diameter to permit free movement of the finger alone through said passageway. The slide plates 28, however, are provided with inclined or conical walls 30, 30, leading to the aperture 29, the said walls being proportioned and located during operation to be struck by the rounded or globular end of the thimble 20 as the finger 18 approaches the recess 28. The slide plates 28 are preferably feathered or tongue-and-groove connected in the frame 27 to slide freely longitudinally therein, and a spring 31 stresses each of the slide plates toward the other to keep the ends of the slide plates in abutment when not forced apart. A guide pin 32 is preferably provided for each spring 31 and extends from frame 27 into and along the respective coiled spring 31 a distance sufficient to retain and guide the spring in its movements.

Thus, when the die block 2 makes its first stroke, the projection 14 compresses and shapes the material in the recess 13 and then the die block recedes, the material being left in the recess 13. The die plungers 5 and 6 are then shifted upward until finger 18 is brought into line with the recess 13, and then the die block 2 makes its second stroke during which the finger 18 enters the recess 13 and flows the material therein to the thimble-like shape to produce the thimble 20, as above stated. Then the die plungers 5 and 6 recede and descend to bring the projection 14 in line with recess 13 for the next first stroke. However, in making this next first stroke, the finger 18 carrying the thimble 20 causes the rounded end of the thimble to strike the beveled walls 30 and thus wedge the slide plates 28 apart against the stress of springs 31 until the abrupt end of thimble 20, that is the end having the opening of the recess within the thimble, passes the rear faces of the plates 28 incident to the opening and closing movement of plates 28. Said plates thus become a direct detent for the thimble 20. With the next return movement of plunger 6, the edges of the thimble strike said detent and the thimble is thereby stripped from the finger 18 and allowed to drop into a chute or other receiver located below and not shown.

While I have disclosed herein an advantageous

and practical form of machine embodying the features of the invention, it is to be understood that the disclosed machine is to be taken as illustrative only and that it is my intention to 5 claim the invention broadly in whatever form its principle may be utilized.

What is claimed is:

1. In mechanism for forming thimble-like shells in the production of capped nuts, the combination with double-stroke header mechanism and a stationary matrix die therein having a dome-shaped cavity, of plunger dies cooperating with the matrix die, one of the plunger dies being shaped to snugly fit within the matrix die 15 and having a bulbous extension for producing a centering depression in a slug or mass of metal forced by said plunger die into the matrix die, and the other plunger die having a finger-like extension proportioned to enter the said centering depression and shape the mass in the matrix die into an elongated, domed, thimble-like shell having substantially the same external domed shape as the internal shape of the matrix die cavity.

2. The combination as claimed in claim 1 with means for stripping the thimble-like shell from the finger-like extension as an incident of the non-forming stroke of said extension.

3. The combination as claimed in claim 1 with means aligned with and spaced below the matrix die for receiving the finger-like extension carrying a thimble-like shell incident to the stroke of the plunger die having the bulbous extension into the matrix die, the said receiving means for the finger-like extension and shell being resiliently stressed for interposing a detent in the path of the shell for stripping the shell from the finger-like extension with the return stroke of the latter.

4. In a machine for forming thimble-like 40 capped nut blanks from slugs of metal, in combination, a stationary female die, a double stroke plunger, a pair of plunger dies carried by the plunger, the first being a preliminary forming die for cooperating with the female die to shape a blank at a first or preliminary blank forming stroke, and the second being a finishing die for 45 cooperating with the female die to further shape the blank to thimble-like form at a second or finishing forming stroke, and each having a non-forming stroke with the plunger, out of alignment with the female die, at the forming stroke of the other, the construction and arrangement being such that a blank placed in the female die is 50 acted upon successively by the plunger dies and is then carried away from the female die by the finishing plunger die, and a stripper formed and mounted to engage the finished blank as the blank is carried forward by the finishing die at the non-forming stroke of said die, and to strip the blank from the die as the die recedes following such non-forming stroke.

5. In a machine for forming thimble-like 65 capped nut blanks from slugs of metal, in combination, a stationary female die, a double stroke plunger, a pair of plunger dies carried by the plunger, the first being a preliminary forming die for 70 cooperating with the female die to shape a blank at a first or preliminary blank form of stroke, and the second being a finishing die for cooperating with the female die to further shape the blank to thimble-like form at a second or 75 finishing forming stroke, and each having a non-forming stroke with the plunger, out of alignment with the female die, at the forming stroke of the other, means for assuring that the blank

will be carried away from the female die by the finishing plunger die, and a stripper formed and mounted to engage the finished blank as the blank is carried forward by the finishing die at the non-forming stroke of said die, and to strip the blank from the die as the die recedes following such non-forming stroke.

6. In a machine for forming thimble-like 10 capped nut blanks from slugs of metal, in combination, a stationary female die, a double stroke plunger, a pair of plunger dies carried by the plunger, the first being a preliminary forming die for 15 cooperating with the female die to shape a blank at a first or preliminary blank forming stroke, and the second being a finishing die for 20 cooperating with the female die to further shape the blank to thimble-like form at a second or finishing forming stroke, and each having a non-forming stroke with the plunger, out of alignment with the female die, at the forming stroke 25 of the other, the construction and arrangement being such that a blank placed in the female die is acted upon successively by the plunger dies and is then carried away from the female die by the finishing plunger die, and a pair of laterally yieldable stripper members formed and mounted to be engaged and cammed apart by a finished blank carried forward by the finishing die at the non-forming stroke of said die, and to engage behind the blank and strip it from the 30 die as the die recedes following such non-forming stroke.

7. In a machine for forming thimble-like 35 capped nut blanks from slugs of metal, in combination, a stationary female die, a double stroke plunger, a pair of plunger dies carried by the plunger, the first being a preliminary forming die for 40 cooperating with the female die to shape a blank at a first or preliminary blank forming stroke, and the second being a finishing die for 45 cooperating with the female die to further shape the blank to thimble-like form at a second or finishing forming stroke, and each having a non-forming stroke with the plunger, out of alignment with the female die, at the forming stroke 50 of the other, the construction and arrangement being such that a blank placed in the female die is acted upon successively by the plunger dies and is then carried away from the female die by the finishing plunger die, and a pair of laterally yieldable stripper slides formed and mounted to be engaged and cammed apart by a finished blank carried forward by the finishing die at the non-forming stroke of said die, and to engage behind the blank and strip it 55 from the die as the die recedes following such non-forming stroke.

8. In a machine, for forming thimble-like 60 capped nut blanks from slugs of metal, in combination, a stationary female die having a dome-shaped cavity therein, a double stroke plunger, and a pair of plunger dies carried by the plunger, the first being a preliminary forming die for 65 cooperating with the female die to shape a blank at a first or preliminary blank forming stroke, and the second being a finishing die for 70 cooperating with the female die at a second or finishing forming stroke to further shape the blank to a domed, thimble-like form having an external contour substantially the same as the dome-shaped cavity of the female die and having an internal contour substantially the same as the external contour of the finishing die.

9. In a machine for forming thimble-like 75 capped nut blanks from slugs of metal, in com-

bination, a stationary female die having a dome-shaped cavity therein, a double stroke plunger, and a pair of plunger dies carried by the plunger, the first being a preliminary forming die for co-operating with the female die to shape a blank at a first or preliminary blank forming stroke, and the second being a finishing die, having a rounded leading end, for cooperating with the fe-

male die at a second or finishing stroke to further shape the blank to a domed, thimble-like form having an external contour substantially the same as the dome-shaped cavity of the female die and having an internal contour substantially the same as the external contour of the finishing die. 5

HEYMAN ROSENBERG.
